RAILWAY TRAFFIC CONTROLLING APPARATUS

Ralph K. Crooks, Sharpsburg, Pa., assignor to
The Union Switch & Signal Company, Swiss-
vale, Pa., a corporation of Pennsylvania

Application November 16, 1940, Serial No. 365,887

8 Claims. (Cl. 246—63)

My invention relates to railway traffic controlling apparatus, and more particularly to train carried train control apparatus responsive to coded current.

Railway traffic controlling apparatus responsive to coded energy is well-known and train carried train control apparatus responsive to coded alternating track circuit current is used. The track circuit customarily includes the track rails of a track section and the alternating current supplied thereto is coded by being periodically interrupted at a preselected rate. Such coded current has alternate on and off periods, current flowing during each on period and no current flowing during each off period. The on and off code periods are ordinarily of equal duration. The current is coded at any one of several different code rates according to different traffic conditions, the code rates of 180, 120 and 75 interruptions per minute being those commonly used to reflect clear, approach-medium and approach traffic conditions, respectively.

A receiving circuit is mounted on the train in inductive relation to the track rails to receive an electromotive force in response to such coded rail current. The electromotive force thus picked up by the train carried receiving circuit has the same frequency as that of the alternating current supplied to the track rails and is of the same code rate as that of the rail current. The electromotive force thus picked up by the receiving circuit is used to control the operation of a code following relay through the medium of an electron tube amplifier, such relay being operated at a rate corresponding to the code rate of the rail current.

The code following relay is used in turn to control the train control apparatus through the medium of a decoding means which is selectively responsive to the rate at which the code following relay is operated and hence in turn is selectively responsive to the code rate of the rail current.

A railway train is commonly provided with a 32 volt source of direct current for supplying current to the train lighting circuit, locomotive headlight circuit and similar equipment. Electron tubes heretofore proposed for train control apparatus are of a type which require a plate voltage of the order of 300 volts for proper operation of the tube, and a motor generator or a dynamotor is usually provided to convert the 32 volts by the usual train carried source to that needed by the electron tube. As an alternative arrangement, a separate generator may be pro-

vided for the train control apparatus. Such special generator, or dynamotor or motor generator add to the cost of the equipment and require maintenance. Low voltage electron tubes which are satisfactorily operated by 32 volts are now available.

In view of the above cited conditions, an object of my invention is the provision in railway traffic controlling apparatus of novel and improved amplifying means for control of a train carried code following relay in response to electromotive forces derived from coded alternating current supplied to the track rails.

Another feature of my invention is the provision of railway traffic controlling apparatus incorporating novel and improved means for control of the grid voltage of a train carried electron tube amplifier in response to an electromotive force derived from coded alternating current flowing in the track rails.

Again, a feature of my invention is the provision of novel and improved low voltage electron tube amplifier for railway traffic controlling apparatus, and wherewith power is made available sufficient for operation of a standard code following relay.

Still another feature of my invention is the provision of a novel direct current electron tube amplifier for railway traffic controlling apparatus.

To attain the above features as well as other advantages of my invention, which will become apparent as the specification progresses, I provide according to my invention a train carried rectifier and a biasing unit comprising a resistor and a condenser in multiple together with a low voltage electron tube amplifier. The biasing unit is connected through the rectifier to the train carried receiving circuit which is mounted in inductive relation to the track rails to receive an electromotive force in response to coded alternating current supplied to the rails. The alternating electromotive force picked up by such receiving circuit is hence rectified and unidirectional current is made to flow in the resistor of the biasing unit and a direct voltage is developed across the terminals of that unit. The time constant of such biasing unit is such that the direct voltage thus developed across its terminals during an on code period is substantially uniform throughout the on period but quickly dies away at the beginning of the next off code period. That is, the direct voltage developed across the biasing unit follows the envelope of the electromotive force picked up by the receiv-

ing circuit. Both the heater and the plate circuits of the electron tube are connected to the usual 32 volt train carried source of current. A current limiting resistor is included in the heater circuit and is disposed in the lead from the cathode of the tube to the negative terminal of the current source. The plate circuit includes the primary winding of an output transformer and a condenser in multiple and the current limiting resistor of the heater circuit. Thus there is developed across this current limiting resistor a voltage drop derived from the heater circuit and the plate circuit currents flowing therethrough. The voltage drop due to the heater circuit current is of a relatively large value and of a given fixed value. That due to the plate circuit current is of a relatively small value and for the purpose of this application can be neglected.

A grid circuit including the biasing unit and the current limiting resistor is connected across the control grid and cathode of the electron tube. The biasing unit is poled so that the voltage developed across its terminals due to the rectification of the electromotive forces picked up from the rail current opposes the voltage drop in the current limiting resistor. Hence the control grid of the electron tube is provided with a fixed negative grid bias voltage equal to the voltage drop in the current limiting resistor and this fixed bias voltage is varied according to the voltage developed across the biasing unit, with the result that the plate circuit current is varied according to the code rate of the electromotive force picked up by the receiving circuit.

A code following relay is connected to the secondary winding of the output transformer. The condenser connected in multiple with the primary winding of the output transformer is effective to by-pass variations of the plate circuit current of a frequency of the order of the frequency of the alternating track rail current, but is ineffective to by-pass variations of the plate circuit current corresponding to the code rate of the track rail current. The code following relay is a polar relay and is operated in the usual manner by the electromotive force induced in the secondary winding of the output transformer in response to variations of the plate circuit current corresponding to the code rate of the track rail current.

The rectifier on the train may be any suitable type and preferably is a diode or a copper oxide rectifier. If a copper oxide rectifier is used then a stage of amplification is preferably interposed between the copper oxide rectifier and the receiving circuit to assure that ample power is available at the input terminal of the copper oxide rectifier. Since the rectifier functions to cause unidirectional current to flow in the resistor of the biasing unit, the electron tube amplifier functions as a direct current amplifier amplifying this direct current flowing in the resistor of the biasing unit.

I shall describe two forms of apparatus embodying my invention, and shall then point out the novel features thereof in claims.

In the accompanying drawing, Figs. 1 and 2 are diagrammatic views, showing two different forms of apparatus, each of which embodies my invention. In the different views, like reference characters are used to designate similar parts.

Referring to Fig. 1, the reference characters 1a and 1b designate the track rails of a railway. These rails 1a and 1b would be formed by the

usual insulated rail joints, not shown, into consecutive track sections, and the rails of each such section would be supplied at times with coded alternating current. In order to better understand my invention, the alternating current will be considered as being of 100 cycles per second since such frequency is widely used in railway traffic controlling apparatus of the type here involved. It is to be understood, however, that my invention is not limited to alternating current of 100 cycles per second, as current of other frequencies may be used. The trackway apparatus for supplying coded current to rails 1a and 1b is not shown since it forms no part of my invention and may be any one of several well-known arrangements. Such trackway apparatus may, for example, be that disclosed by Letters Patent of the United States No. 1,986,679, granted January 1, 1935, to L. V. Lewis, for Railway traffic controlling apparatus, and it is sufficient for the present application to point out that the track rails 1a and 1b of Fig. 1 are supplied with alternating current coded at the code rates of 180, 120 and 75 cycles per minute in response to clear, approach-medium and approach traffic conditions, respectively.

Two inductors 2 and 3 are mounted on a train in inductive relation to rails 1a and 1b, respectively. Inductors 2 and 3 are connected to a receiving circuit which also includes a condenser 4 and the primary winding 5 of a transformer T1. A condenser 6 is connected across a secondary winding 7 of transformer T1, and the receiving circuit together with transformer T1 are tuned to resonance at the frequency of the alternating current and in the case here assumed for illustration they are tuned to resonance at 100 cycles per second. It follows that an electromotive force appears across the terminals of secondary winding 7 and condenser 6 in response to each on period of the coded rail current, and the electromotive force quickly dies away at the beginning of each off period of the rail current. Such electromotive force is an alternating electromotive force of 100 cycles per second and is coded at a code rate corresponding to the code rate of the rail current.

A rectifier in the form of an indirect heated diode tube DT is mounted on the train. Tube DT is provided with a plate 8, a cathode 9 and a filament 10. The filament 10 of tube DT is heated by being connected across the terminals B32 and N32 of a current source TB, a current limiting resistor 62 being preferably interposed in the circuit. As here shown the current source TB is a battery and preferably this battery is the usual 32 volt battery carried on the train for supplying power to the usual train lighting circuits.

A biasing unit BU consisting of a resistor 12 and a condenser 11 in multiple is provided. The biasing unit BU is included in a circuit which can be traced from the left-hand terminal of unit BU over secondary winding 7 of transformer T1 and condenser 6 in multiple, plate 8 of tube DT, intervening tube space to cathode 9 and to the right-hand terminal of unit BU.

The diode tube DT functions to rectify the alternating electromotive force appearing across secondary winding 7 of transformer T1 and unidirectional current is caused to flow in resistor 12 of the unit BU. The condenser 11 serves to maintain during the interval between successive cycles of the electromotive force the voltage across resistor 12 and hence a direct voltage of

nearly the peak voltage of the electromotive force is developed across the terminals of unit BU, the polarity of such direct voltage being that indicated by the plus and minus signs placed at unit BU. The time constant of the circuit including resistor 12 and condenser 11 is such that the voltage thus developed across the terminals of the unit BU during an on code period of the electromotive force does not die away between the successive cycles of the electromotive force but quickly dies away during the next off period of the electromotive force. It follows that the direct voltage developed across the unit BU substantially follows the envelope of the rectified electromotive force and has on and off periods which are substantially in step with the on and off periods of the electromotive force created across the primary winding 7 and indirectly in step with the on and off periods of the coded rail current. The control effected by such direct voltage will shortly appear.

A low voltage electron tube TT is also mounted on the train. Tube TT may be of any one of several types and may be a tetrode having a plate 13, a cathode 14, a control grid 15, another grid 16 and a filament 17. Tube TT is heated by its filament 17 being connected across terminals B32 and N32 of the current source, a current limiting resistor 18 being disposed in the lead between the negative side of filament 17 and the negative terminal of the current source. Another grid 16 is connected to the positive terminal of filament 17 and the cathode 14 is connected to the negative terminal of filament 17 as is customary for such electron tubes. Hence current limiting resistor 18 is disposed in the lead between cathode 14 and the negative terminal N32 of the current source.

Tube TT is provided with a grid circuit that can be traced from control grid 15 over wire 19, biasing unit BU and current limiting resistor 18 to cathode 14. It is clear that the voltage drop in resistor 18 caused by the heater circuit current provides a fixed negative grid bias voltage for the tube TT. Also the direct voltage developed across biasing unit BU in the manner explained hereinbefore opposes the voltage created across resistor 18 and a resultant grid bias voltage is created. In other words, the normal fixed negative grid bias voltage for tube TT is varied by the voltage developed across unit BU due to the rectified electromotive force picked up from the track rails and the grid voltage is varied substantially in step with the on and off code periods of the rail current.

A plate circuit for tube TT is formed from positive terminal B32 of battery TB over primary winding 20 of output transformer T2 in multiple with a condenser 21, plate 13 of tube TT, intervening tube space to cathode 14 and current limiting resistor 18 to negative terminal N32. Since the voltage developed across unit BU decreases the negative bias voltage for control grid 15, the plate circuit current is correspondingly increased during each on code period. Hence the average value of the plate circuit current is varied substantially in step with the code period of the received electromotive force and an electromotive force is induced in secondary winding 22 of the output transformer T2 in response to each such variation of the average value of the plate circuit current.

A polar code following relay MS is connected to secondary winding 22 of transformer T2, the arrangement being such that contact member

23 of relay MS is operated to the left-hand position as viewed in Fig. 1 to engage normal contact 24 when an electromotive force is induced in secondary winding 22 due to an increase of the plate circuit current, and contact member 23 is operated to the right-hand position to engage reverse contact 25 in response to the electromotive force induced in secondary winding 22 when the average value of the plate circuit current is decreased. Operation of contact member 23 of relay MS to alternately engage contacts 24 and 25, causes direct current from battery TB to be alternately supplied to the two portions of the primary winding 26 of a decoding transformer T3 whose secondary winding 27 is connected to the input terminals of a decoding means DM. Thus with relay MS operated an alternating electromotive force is induced in secondary winding 27 of decoding transformer T3 and applied to the decoding means DM, the frequency of such electromotive force corresponding to the rate at which relay MS is operated.

The decoding means DM may take any one of several well-known forms and may be the tuned circuit arrangement covered by Letters Patent of the United States No. 1,773,515, granted August 19, 1930, to C. C. Buchanan, for Railway traffic controlling apparatus. It is sufficient for the instant application to point out that control relays A, R and L connected to the output side of decoding means DM are selectively controlled according to the frequency of the electromotive force applied to the input terminal of the decoding means. As here shown relays A and L are effectively energized and picked up when decoding means DM is supplied with electromotive force of a frequency created by operation of relay MS at a rate corresponding to the 180 code rate of the track rail current. Relays R and L are effectively energized and picked up and relay A is released when decoding means DM is supplied with an electromotive force of a frequency created by operation of relay MS at a rate corresponding to the 120 code rate of the rail current, and relay L is effectively energized and picked up and relays A and R are released when decoding means DM is supplied with an electromotive force of a frequency corresponding to operation of relay MS at the 75 code rate of the rail current. Furthermore, all three control relays A, R and L are released when code following relay MS is inactive.

Control relays A, R and L are used to control the operating circuits of a train control means, here shown as a cab signal CS, signal CS being a four-position color light signal. The operating circuits are those commonly employed and as here shown when relay A is picked up closing front contact 28 an operating circuit easily traced is completed for lamp 29 and that lamp is illuminated to cause the signal CS to display a clear signal indication. When relay A is released closing back contact 30 and relay R is picked up closing front contact 31, an operating circuit is formed for lamp 32 and that lamp is illuminated to cause signal CS to display an approach-medium indication. When relays A and R are released, closing back contacts 30 and 33, respectively, and relay L is picked up to close front contact 34, an operating circuit is formed for lamp 35 and that lamp is illuminated to cause signal CS to display an approach signal indication. When relays A, R and L are released, closing back contacts 30, 33 and 36, respectively, an

operating circuit is formed from lamp 37 and that lamp is illuminated to cause signal CS to display a slow speed signal indication.

In describing the operation of the apparatus of Fig. 1, it is to be observed that normally the electron tube TT is provided with a fixed negative grid bias voltage due to the voltage drop across current limiting resistor 18 and current of a steady given value flows in the plate circuit. I shall assume that current coded at the 180 code rate is supplied to rails 1a and 1b to reflect clear traffic conditions. Under this condition an alternating electromotive force of the 180 code rate is picked up by the receiving circuit and made to appear across secondary winding 7 of transformer T1. This alternating electromotive force is rectified by diode tube DT and unidirectional current flows in resistor 12 of the biasing unit DU so that a direct voltage nearly equal to the peak value of the electromotive force picked up by the receiving circuit is developed across the terminals of the unit BU. This direct voltage across unit BU remains substantially uniform in value during the on period of the coded current but quickly dies away at the start of the following off code period due to the time constant of the unit. That is to say, the direct voltage across unit BU follows the envelope of the electromotive force picked up by the receiving circuit. The voltage developed across unit BU opposes the voltage drop through resistor 18 and consequently causes the grid 15 of tube TT to be less negative in potential with respect to the cathode 14 during each on code period. Hence the average value of the plate circuit current is increased during each on code period. Such increase in the average value of the plate circuit current induces in secondary winding 22 of output transformer T2 an electromotive force of a polarity as required to operate relay MS to its left-hand position. At the start of the following off code period, the voltage of unit BU dies away and the biasing voltage of tube TT returns to its normal fixed value so that the plate circuit current decreases to its given normal value. This decrease in the average value of the plate circuit current induces in secondary winding 22 an electromotive force of a polarity opposite to that induced when the plate circuit increased and relay MS is operated to its right-hand position. Since the rail current is of the 180 code rate, the code following relay MS is operated at a corresponding code rate and as pointed out hereinbefore, the control relay A is effectively energized and picked up in response to such operation of the code following relay and lamp 29 is illuminated causing signal CS to display a clear signal indication.

It is to be seen therefore that the value of the current flowing in the plate circuit of tube TT is in accordance with the envelope of the alternating electromotive force picked up by the receiving circuit, and code following relay MS is operated in the usual manner with substantially equal on and off periods. Since the alternating electromotive force picked up by the receiving circuit is rectified and unidirectional current flows in resistor 12 of the biasing unit, which in turn causes a direct voltage to be developed across the terminals of that unit, it follows that tube TT of Fig. 1 functions as direct current amplifier, amplifying the direct current flowing in resistor 12 of the biasing unit.

When current coded at either the 120 or 75 code rate is supplied to the track rails 1a and 1b, the operation of the apparatus of Fig. 1 is the

same except for the fact that the code following relay MS is operated at a rate corresponding either to the 120 or 75 code rate of the rail current and such operation of relay MS in turn controls the control relays so that relay R is picked up for the 120 code rate to cause the display of the approach medium signal lamp 32, and relay L only is picked up in response to the 75 code rate to cause the display of approach signal lamp 35.

It is to be pointed out that in the event no current is supplied to the track rails and no electromotive force is picked up by the receiving circuit, then the normal fixed bias voltage for tube TT prevails and the given steady value of direct current flows so that no transfer of energy is effected in transformer T2 and relay MS is inactive causing relays A, R and L to be all released so that the slow speed signal lamp 37 is illuminated.

Referring to Fig. 2, the diode rectifier tube DT of Fig. 1 is replaced by a copper oxide rectifier CR and a stage of amplification including a low voltage electron tube FT is inserted between the rectifier CR and the train carried receiving circuit.

Electron tube FT is preferably of the same type as tube TT. The filament 44 of tube FT is heated by being connected across battery TB through a current limiting resistor 45, cathode 41 is connected to the negative end of filament 44 and grid 43 is connected to the positive end of the filament. The grid circuit for tube FT includes control grid 42, a grid leak condenser unit GL, secondary winding 7 of transformer T1 and condenser 6 in multiple, and the upper portion of resistor 45 to cathode 41. The plate circuit of tube FT includes the positive terminal B32 of the current source, primary winding 46 of transformer T4, plate 48 of tube FT, intervening tube space to cathode 41 and current limiting resistor 45 to the negative terminal N32. The secondary winding 47 of transformer T4 is connected to the input terminals of rectifier CR and the output terminals of rectifier CR are connected across the biasing unit BU which consists of resistor 12 and condenser 11 the same as in Fig. 1.

It is clear that the alternating electromotive force appearing across the secondary winding 7 of transformer T1 due to the coded rail current is amplified by tube FT and an alternating electromotive force is applied to the rectifier CR and rectified to cause unidirectional current to flow in resistor 12 of unit BU. This current flowing in resistor 12 develops a direct voltage across the terminals of the unit BU in the same manner as described in connection with Fig. 1.

The grid circuit for tube TT of Fig. 2 is similar to that described in Fig. 1 and includes control grid 15, biasing unit BU, current limiting resistor 45 and cathode 14. It is to be observed that the unit BU of Fig. 2 is disposed so that the voltage developed across the unit opposes the negative voltage which is created across resistor 45 due to the heater currents of tubes FT and TT flowing therethrough.

The plate circuit for tube TT, master relay MS, decoding means DM, control relays A, R and L, cab signal CS and the circuit associated therewith are the same in all respects to those described in Fig. 1 and the description thereof need not be repeated.

It is clear that the apparatus of Fig. 2 will operate in substantially the same manner as the apparatus of Fig. 1 in response to coded alternat-

ing current supplied to the rails $1a$ and $1b$ except for the fact that the electromotive force picked up by the receiving circuit is first amplified at tube FT before it is applied to the input terminals of the rectifier. Also the rectifier CR of Fig. 2 is a full wave rectifier whereas the diode tube DT of Fig. 1 is a half wave rectifier. When the electromotive force picked up from the track rails is first amplified the power available at the input terminals of the rectifier is increased to a value that it is possible to use a rectifier of the copper oxide rectifier type. If the rail current is of relatively high energy level, the first stage tube FT may not be needed.

It is to be pointed out in connection with Fig. 2 that the grid leak condenser unit GL functions to maintain a substantially uniform value of power as applied to the rectifier, and hence as applied to the code following relay MS for operation thereof throughout the usual range of normal to maximum value of rail current and code distortion is avoided. This feature however is no part of my present invention.

It is apparent, therefore, that I have provided two forms of novel and improved low voltage electron tube amplifiers for use with train carried train control apparatus.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In railway traffic controlling apparatus for use with a receiving circuit mounted on a train in inductive relation to the track rails to receive in response to coded alternating current supplied to the rails an electromotive force having an envelope substantially in step with the on and off periods of the coded current, the combination comprising, a train carried biasing unit including a resistor and a condenser in multiple, a train carried rectifier, a circuit including said rectifier to couple said biasing unit to said receiving circuit to cause unidirectional current to flow in the resistor of said unit and a direct voltage to be developed across said biasing unit in response to said received electromotive force, said biasing unit constructed to have a predetermined time constant to cause said direct voltage to substantially follow the envelope of said received electromotive force; a train carried electron tube having a plate, a cathode and a control grid; a grid circuit including said biasing unit connected across said control grid and said cathode to control the potential of the grid with respect to said cathode by said direct voltage, a plate circuit including a source of current and a winding connected across said plate and cathode, and a code following relay coupled to said plate circuit winding effectively operated by the variations of the plate circuit current in response to such control of the potential of the grid with respect to the cathode.

2. In railway traffic controlling apparatus for use with a receiving circuit mounted on a train in inductive relation to the track rails to receive an alternating electromotive force in response to alternating current coded at a given code rate supplied to the rails, the combination comprising, a train carried biasing unit including a resistor and a condenser in multiple, a train

carried rectifier; a circuit including said rectifier, said biasing unit and a winding coupled to said receiving circuit to cause a direct current of said code rate to flow in the resistor of said unit; a train carried electron tube having a plate, a cathode and a control grid; a grid circuit including said biasing unit connected across the control grid and cathode of said tube, a plate circuit including a current source and a winding connected across the plate and cathode of said tube, and a code following relay coupled to said plate circuit winding effectively operated at said code rate due to the amplification of the direct current flowing in the resistor of said biasing unit as effected by said electron tube.

3. In railway traffic controlling apparatus for use with a receiving circuit mounted on a train in inductive relation to the track rails to receive an electromotive force in response to coded alternating current supplied to the rails, the combination comprising, a train carried biasing unit including a resistor and a condenser in multiple, a train carried rectifier, a circuit including said rectifier and a winding coupled to said receiving circuit connected to said biasing unit to develop a direct voltage across the terminals of said biasing unit in response to such received electromotive force; a train carried electron tube having a plate, a cathode and a control grid; a heater circuit including a circuit source and a current limiting resistor for said tube and having said current limiting resistor disposed between said cathode and the negative terminal of the current source, a grid circuit including said biasing unit and said current limiting resistor connected across said control grid and cathode, said biasing unit poled to cause the voltage developed across its terminals to oppose the voltage drop occurring across said current limiting resistor to control the grid voltage each on period of said coded current, a plate circuit including a current source and a winding connected across the plate and cathode of said tube, and a code following relay coupled to said plate circuit winding effectively operated by the variations of the plate circuit current caused by such control of the grid voltage.

4. In railway traffic controlling apparatus for use with a receiving circuit mounted on a train in inductive relation to the track rails to receive an electromotive force in response to coded alternating current supplied to the rails, the combination comprising, a train carried biasing unit including a resistor and a condenser in multiple, a train carried rectifier, means including said rectifier to connect said biasing unit to a winding coupled to said receiving circuit to cause unidirectional current to flow in the resistor of said unit and develop a direct voltage across the terminals of the unit in response to said received electromotive force; a train carried electron tube having a plate, a cathode and a control grid; a grid circuit connected across said control grid and cathode and including said biasing unit and another biasing means, said biasing means effective to provide a predetermined negative grid bias voltage and said biasing unit poled to cause the voltage developed across its terminals to oppose said predetermined bias voltage to control the grid voltage in response to said coded rail current, a plate circuit for said tube and including a winding and a current source, and a code following relay coupled to said plate circuit winding ef-

fectively operated by the variations of the plate circuit current caused by such control of the grid voltage.

5. In railway traffic controlling apparatus for use with a receiving circuit mounted on a train in inductive relation to the track rails to receive an electromotive force in response to alternating current coded at a given code rate supplied to the rails, the combination comprising, a train carried biasing unit including a resistor and a condenser in multiple, a train carried rectifier, means including said rectifier to connect said biasing unit to a winding coupled to said receiving circuit to cause unidirectional current to flow in the resistor of said unit and develop a direct voltage across the terminals of the unit in response to said received electromotive force; said biasing unit having a time constant effective to cause the voltage developed across said unit to substantially follow the envelope of said received electromotive force; a train carried electron tube having a plate, a cathode and a control grid; a grid circuit connected across said control grid and cathode and including said biasing unit and another biasing means, said biasing means effective to provide a predetermined fixed grid bias voltage and said biasing unit disposed to cause the voltage developed across the unit to oppose said fixed bias voltage to cause a variation in the potential of the grid with respect to the cathode to vary substantially in step with the on and off periods of said received electromotive force, a plate circuit connected across the plate and cathode of said tube and including a winding and a current source, and a code following relay coupled to said plate circuit winding to operate the relay in response to the variations of the plate circuit caused by said variation of the potential of the grid with respect to the cathode.

6. In railway traffic controlling apparatus for use with a receiving circuit mounted on a train in inductive relation to the track rails to receive an electromotive force in response to alternating current coded at a given code rate supplied to the rails, the combination comprising, a train carried biasing unit including a resistor and a condenser in multiple, a train carried rectifier, means including said rectifier to connect said biasing unit to a winding coupled to said receiving circuit to cause unidirectional current to flow in the resistor of said unit and develop a direct voltage across the terminals of the unit in response to said received electromotive force; a train carried 32 volt electron tube having a plate, a cathode and a control grid, a train carried 32 volt source of direct current, a heater circuit for said tube including said source and a current limiting resistor with the resistor disposed between said cathode and the negative terminal of the current source, a grid circuit connected across the control grid and cathode and including in series said biasing unit and said current limiting resistor, said biasing unit disposed to cause the voltage developed across its terminals to oppose the voltage drop in said current limiting resistor to vary the potential of the grid with respect to the cathode in step with the on and off periods of the received electromotive force, a plate circuit to connect said 32 volt source of current across the plate and cathode of the tube, a code following relay, and a transformer having a primary winding interposed in said plate circuit and a secondary winding connected to said code following relay to operate the relay by the

variations of the plate circuit current caused by said variations of the potential of the grid with respect to the cathode.

7. In railway traffic controlling apparatus for use with a receiving circuit mounted on a train in inductive relation to the track rails to receive an alternating electromotive force of a given code rate when alternating current coded at said code rate is supplied to the rails, the combination comprising, a first and a second electron tube mounted on the train, a train carried biasing unit including a resistor and a condenser in multiple, a train carried rectifier, a first and a second transformer mounted on the train, a grid circuit for said first tube and including a winding coupled to said receiving circuit, a plate circuit for said first tube and including a current source and a primary winding of said first transformer, means including said rectifier to connect said biasing unit to a secondary winding of said first transformer to cause direct current of said code rate to flow in the resistor of said biasing unit in response to said received electromotive force as amplified by said first tube, a grid circuit for said second tube and including said biasing unit, a plate circuit for said second tube and including a current source and a primary winding of said second transformer, and a code following relay connected to a secondary winding of said second transformer effectively operated at said code rate due to the amplification of the direct current flowing in the resistor of said biasing unit as effected by said second tube.

8. In railway traffic controlling apparatus for use with a receiving circuit mounted on a train in inductive relation to the track rails to receive an alternating electromotive force of a given code rate when alternating current coded at said code rate is supplied to the rails, the combination comprising, a first and a second electron tube mounted on the train, a train carried biasing unit including a resistor and a condenser in multiple, a train carried rectifier, a first and a second transformer mounted on the train, a train carried battery, a heater circuit for said first tube connected to said battery, a heater circuit for said second tube connected to said battery and including a current limiting resistor disposed in the lead between the cathode of that tube and the negative terminal of said battery, a grid circuit for said first tube and including a winding coupled to said receiving circuit, a plate circuit for said first tube and including said battery and a primary winding of said first transformer, means including said rectifier to connect said biasing unit to a secondary winding of said first transformer to develop a direct voltage across said biasing unit in response to each on period of said received electromotive force as amplified by said first tube, a grid circuit for said second tube and including said biasing unit and said current limiting resistor, a plate circuit for said second tube and including said battery and a primary winding of said second transformer, and a code following relay connected to a secondary winding of said second transformer effectively operated at said code rate due to the grid voltage control of said second tube as effected by said direct voltage developed across said biasing unit and the voltage drop across said current limiting resistor caused by the heater current flowing therethrough.
